UNITED STATES PATENT OFFICE.

DAVID McGENNIS, OF LEAKSVILLE, NORTH CAROLINA, ASSIGNOR, BY MESNE ASSIGNMENTS, TO THE CAROLINA COTTON & WOOLEN MILLS CO., OF SPRAY, NORTH CAROLINA, A CORPORATION OF NORTH CAROLINA.

NETHERGARMENT.

1,373,341.

Specification of Letters Patent. Patented Mar. 29, 1921.

Application filed June 14, 1919. Serial No. 304,929.

To all whom it may concern:

Be it known that I, DAVID McGENNIS, a citizen of the United States, residing at Leaksville, in the county of Rockingham and State of North Carolina, have invented 5 certain new and useful Improvements in Nethergarments, of which the following is a specification.

This invention relates to improvements in 10 nether garments.

In children's drawers and in union suits of the drop seat type, the principal strain occurs at the side plackets of the garment, the legs of the garment being in time torn 15 or ripped in a downward direction at the outer sides from the lower ends of the plackets. It is, therefore, one object of the present invention to provide a nether garment of this type with a novel form of hem for the 20 placket which hem will be of a construction to effectually prevent enlargement of the placket through tearing and will consequently reinforce the garment at the plackets so as to prevent the eventual tearing of the 25 legs of the garment at the points above referred to.

Ordinarily, undershirts are manufactured with a plain shoulder seam and as a result there is nothing provided to prevent 30 stretching of the shoulder of such a garment so that the lower ends of the sleeves of the shirt are liable to work down below the sleeves of the outer garments and become exposed to view, likewise causing dis- 35 comfiture to the wearer. It is therefore, also an object of the present invention to adapt the same to the shoulder seam of an undershirt so as to effectually reinforce this portion of the garment and prevent stretch- 40 ing of the same.

Another object of the invention is to provide means whereby garments of the two types mentioned may be reinforced in the respects referred to so as to prevent stretch- 45 ing and tearing, the reinforcement being capable of application to or embodiment in the garment by a single operation of stitching so that so far as labor is concerned no more expense will be involved than in the 50 stitching of a plain seam.

In the drawings:

Figure 1 is a perspective view illustrat-

ing a pair of children's drawers, the side plackets of which are equipped with the reinforcement embodying the present invention. 55

Fig. 2 is a detail fragmentary perspective view, partly in section, illustrating the lower portion of one of the plackets.

Fig. 3 is a view similar to Fig. 2 but 60 illustrating the reinforcement separated from the garment prior to being stitched thereto.

Fig. 4 is a perspective view of an undershirt equipped with the reinforcement of the 65 present invention.

Fig. 5 is a fragmentary sectional perspective view illustrating in detail the reinforcement of the shoulder seam of the shirt shown in Fig. 4. 70

Fig. 6 is a view similar to Fig. 5 but illustrating the reinforcement separated from the garment.

Fig. 7 is a view looking at the inner side of 75 the shoulder portion of the garment.

Fig. 8 is a perspective view illustrating the application of the invention to a drop seat union suit.

In that embodiment of the invention shown in Figs. 1, 2 and 3 of the drawings, 80 the numeral 1 indicates in general a pair of children's drawers and the numeral 2 indicates the side plackets thereof. Ordinarily, these plackets are provided at their margins with an ordinary turned over hem 85 which, as before stated, soon breaks through due to the strains imposed on this portion of the garment, with the result that the legs of the garment become torn along one or more lines extending from the plackets. In 90 carrying out the present invention, the margin of each placket is formed with a simple hem 3 and disposed over this hem at the outer side of the garment is a length of tape 4 extending continuously around the margin 95 of the placket. This tape 4 is non-elastic and is of a quality which will prove durable and which cannot be readily worn or broken through. The garment is then cross stitched along the margin of the placket, as indicated 100 by the numeral 5, the stitches passing through the hem 3 and through the marginal portions of the tape 4, as clearly shown in Fig. 2 of the drawings. In this manner

the plackets of the garment are effectually reinforced and the same is true of the plackets in the drop seat union suit shown in Fig. 8 of the drawings.

- 5 In the embodiment of the invention shown in Figs. 4 to 7 inclusive, the numeral 6 indicates an undershirt, 7 the sleeves thereof, 8 the shoulders, and 9 the shoulder seams. Ordinarily, these seams are of simple form 10 and as before stated there is nothing to prevent stretching of the shoulders of the garments so that the lower ends of the sleeves will ride down below the lower ends of the sleeves of the outer garment or garments. 15 In order to prevent this and also to reinforce this portion of the garment, each marginal portion of the shoulder of the garment at the shoulder seam is formed with a simple hem indicated by the numeral 10, as 20 clearly shown in Figs. 5 and 6 of the drawings, and then when these hems are brought together in the manner shown in Fig. 5, a non-elastic strip of tape 11 is laid over the seam and secured in place by cross stitching 25 12, the stitches passing through the mar-

ginal portions of the tape and through the said hems 10.

From the foregoing it will be observed that in both instances the garment is reinforced by a non-elastic tape which is disposed over and united to a hem so that while the material of the garment itself may be relatively elastic and quite readily unraveled, it is effectually prevented from stretching or unraveling at the point of reinforcement. 30 35

Having thus described the invention, what is claimed as new is:

A garment having a placket provided at its margin with a hem formed by folding over the said margin and uniting the same to the garment proper continuously along the placket, a strip of non-elastic material disposed over the hem, and stitching uniting the strip to the said garment and hem 40 along the margins of the strip and along the fold providing the hem and adjacent the attached edge of the hem. 45

In testimony whereof I affix my signature.
DAVID McGENNISS. [L.s.]
